(57) **CLAIM**

The ornamental design for traveler beverage container, as shown and described.

DESCRIPTION

FIG. 1 is a top perspective view of a traveler beverage container showing my new design.

FIG. 2 is a front view thereof.

FIG. 3 is a left side view thereof.

FIG. 4 is a right side view thereof.

FIG. 5 is a front view thereof.

FIG. 6 is a top plan view thereof; and,

FIG. 7 is a bottom plan view thereof.

The broken lines in FIGS. 1 and 6 form no part of the claimed design.
